CLOTHES DRIER

William E. Horstotte, Spokane, Wash.

Application November 4, 1943, Serial No. 508,964

5 Claims. (Cl. 211—178)

This invention relates to a clothes drier and it is one object of the invention to provide a drier adapted for use indoors and having a main frame disposed upright and racks carried by the main frame and adapted to be supported in an extended position for use at sides of the frame, the racks being foldable to a collapsed position close to sides of the frame when not in use.

Another object of the invention is to provide the frame with upper and lower racks pivotally mounted to opposite sides thereof and having supporting legs mounted for swinging movement from a raised or folded position to a depending position in which they support the racks, the legs of the upper racks constituting means for releasably securing the legs of the lower racks in depending position.

Another object of the invention is to provide the upper racks with additional supporting members and thus permit the upper racks to be supported in a raised position while the lower racks are folded.

Another object of the invention is to so form the racks that certain of their longitudinally extending rods may constitute pivots for mounting the racks to the frame and permit the racks to be raised and lowered.

Another object of the invention is to provide improved brackets for pivotally connecting the legs of the lower racks with side bars of the racks, portions of the brackets being engageable by lower ends of legs of the upper racks to hold the legs of the lower racks extended for use.

Another object of the invention is to provide a clothes drier which is of light weight but strong and not liable to collapse when in use.

The invention is illustrated in the accompanying drawing, in which:

Fig. 1 is a perspective view of the improved clothes drier with its racks extended and supported in position for use.

Fig. 2 is a fragmentary sectional view on an enlarged scale, on the line 2—2 of Fig. 1.

Fig. 3 is a perspective view of one of the brackets for pivotally connecting legs of the lower racks with the racks.

Fig. 4 is a fragmentary view on the line 4—4 of Fig. 1.

This clothes drier has a main frame provided with corner posts or uprights 1 which have their lower ends secured to base members or feet 2 and are maintained in spaced parallel relation to each other by upper and lower cross bars 3. Bracing bars 4 extend longitudinally of the frame between

upper ends of the corner posts and the feet 2 are braced against movement toward each other by a bar 5. It will thus be seen that the frame is formed of posts and bars which are firmly secured to each other and that the frame will be very strong and, at the same time, of light weight.

Upper and lower racks 6 and 7 are disposed at opposite sides of the main frame and each has end bars 8 between which are mounted a plurality of longitudinally extending rods 9. Referring to Fig. 4, it will be seen that the inner rod of each rack projects outwardly from its end bars, the projecting end portions of the inner rods constituting pivots 9' which pass through openings in the cross bars 3 of the frame and pivotally mount the racks for vertical swinging movement from a lowered position close to sides of the frame to a raised or extended position for use. Spacers 10 are employed to hold the side bars of the racks spaced from the cross bars 3 and allow the racks to be easily swung to folded or extended position.

In order to support the racks in raised or extended position for use, the lower racks have been provided with legs 11 and the upper racks with corresponding legs 12. The legs are carried by end bars of the racks and each is pivotally mounted for swinging movement longitudinally of the rack supported thereby by hinge brackets 13 which are secured against under faces of the end bars by pins 14 which may be bolts or rivets. The brackets are disposed at opposite sides of the legs and connected therewith by pivot pins 15 which may be bolts or rivets. Between their hinge brackets 13, the lower legs carry latching brackets or keepers 16 which extend longitudinally of the legs and are firmly secured thereby by the pins 15 and by additional pins 17, the pins 15 and 17 passing through ears 18 which project inwardly from opposite sides of the keepers against opposite side faces of the legs. Each keeper has its upper end formed with a bill 19 which extends across the upper face of the end bar 8 to which the leg is connected and each bill is formed with an opening 20 registering with a socket 21 formed in the end bar so that the corresponding leg 12 of the upper rack may have its lower end engaged in the aligned opening and socket as shown in Fig. 2. By this arrangement, the legs of the upper racks serve as fasteners for securing the legs of the lower racks in position to support the lower racks extended and, likewise, the legs of the upper racks are secured in position to support the upper racks extended. When it is desired to fold the racks to a collapsed position against sides of the main frame, it is merely nec-

essary to raise the upper racks slightly and withdraw lower ends of their legs from the openings 20 and the sockets 21. The legs are then swung upwardly under the racks and rings or loops 22 slid along the rods carrying the rings until they are engaged about the legs. The racks may then be lowered to a folded position against sides of the main frame. In order that the upper racks may be raised to an extended position for use without raising the lower racks, there have been provided break-joint brackets or braces 23 which are moved to extended position for supporting the upper racks as the upper racks are swung upwardly into position for use. It will thus be seen that either the upper racks or the lower 15 racks may be used without it being necessary to raise both the upper racks and the lower racks.

Having thus described the invention, what is claimed is:

1. A clothes drier comprising a main frame, upper and lower racks at opposite sides of said frame pivotally mounted for swinging movement from lowered folded position against the frame to a raised position in which they extend horizontally from the frame for use, supporting legs for the upper and lower racks and pivotally mounted adjacent the outer ends of the racks for swinging movement from folded position against the racks to depending position for supporting the racks, and keepers carried by the lower legs and engageable by means of openings with the upper legs to releasably hold both the upper legs and the lower legs extended for use.

2. A clothes drier comprising a main frame, upper and lower racks at opposite sides of said frame pivotally mounted for swinging movement from lowered folded position against the frame to raised position in which they extend horizontally from the frame for use, supporting legs for the upper and lower racks and pivotally mounted at the outer ends of the racks for swinging movement from folded position against the racks to depending position for supporting the racks, and means for effecting interlocking engagement between companion upper and lower legs and releasably holding both in depending position for use.

3. A clothes drier comprising a frame, upper and lower racks having end bars at a side of said frame pivotally mounted for vertical swinging from a lowered collapsed position to a raised position in which they extend horizontally from the frame, legs pivoted to said racks adjacent the outer ends for swinging movement from folded position under the racks to depending position for use, legs of the upper rack being disposed over legs of the lower rack in alignment therewith

when the legs are lowered, keepers carried by the lower legs and extending from the upper ends thereof and provided with lips for overlapping ends of the lower racks when the lower legs are lowered, the end bars of the lower rack being formed with sockets, and the lips being formed with openings alining with the sockets whereby lower ends of the upper legs may be engaged with the alined openings and sockets and companion upper and lower legs releasably held extended in position for use.

4. A clothes drier comprising a frame having uprights and cross bars mounted between the uprights, upper and lower racks at a side of the frame having end bars and rods extending between the end bars, said racks being pivotally mounted for vertical swinging movement to raised and lowered positions, supporting legs for said racks, brackets carried by said end bars near the outer ends and pivotally mounting the legs for swinging longitudinally of the racks to raised and lowered positions, loops slideable along rods of said racks for engaging about the legs and releasably holding the legs raised, and latching members carried by the lower legs for engagement with the upper legs to releasably hold the upper and lower legs in lowered position for use.

5. A clothes drier comprising a frame having uprights and cross bars mounted between the uprights, upper and lower racks at a side of the frame having end bars and rods extending between the end bars, said racks being pivotally mounted for vertical swinging movement to raised and lowered positions, supporting legs for said racks, brackets carried by said end bars near the outer ends and extending downwardly therefrom, the brackets carried by each end bar being spaced from each other longitudinally thereof, pivot pins passing through the legs and the brackets, a keeper fitting against the outer side face of each leg of the lower rack and having ears at its side edges overlapping the leg and formed with openings through which the pivot pin for the leg passes, a fastener passing through the leg and the ears for holding the keeper firmly in place with a portion projecting from the upper end of the leg and formed with a lip for overlapping the end bar of the rack beneath which the leg is pivotally mounted, the end bars of the lower rack being formed with sockets and the lips of the keepers being formed with openings for registering with the sockets when the lower racks are in position for use whereby the upper legs may have their lower ends engaged in registering openings and sockets, and releasably hold the upper and lower legs in lowered position.
